UNITED STATES PATENT OFFICE

DRAFT REGULATOR

George Lucas Donovan and William Arthur Fox,
Vancouver, British Columbia, Canada

Application November 1, 1933, Serial No. 696,222
In Canada December 19, 1932

1 Claim. (Cl. 236—93)

The invention relates to improvements in machines or devices for regulating stack velocity or draft in smokepipes, flues, chimneys or stacks; and the objects of our invention are to accomplish this end automatically, with a simply constructed and strongly built self-contained machine or device, simply and easily installed, with few parts, and which may be readily accessible for inspection or repair, and generally to adapt itself to better perform the functions required of it.

We attain these objects by the mechanism illustrated in the accompanying drawing, in which—

15 Fig. 1 shows a front view of the device with detail omitted.

Fig. 2 is a plan view of the detail omitted from Fig. 1.

Fig. 3 is another view of single main casting 20 as shown in Fig. 2, but without other parts.

Fig. 4 shows front view of revolving quadrant shaped portal.

Fig. 5 shows side view of quadrant shaped portal as shown in Fig. 4.

25 Fig. 6 shows front view of concave spring.

Fig. 7 shows washer.

Fig. 8 shows side view of bimetal thermostatic coil.

Fig. 9 shows shaft with split pin.

30 Similar letters refer to similar parts throughout the several views.

Referring to the drawing:

1 represents the main casting to which is attached one end of bimetal coil 6 through hole 35 in coil by screw 12. Through hole in other end of bimetal coil 6 is split pin 11, which holds that end of bimetal coil from slipping sideways out of slot or fork in shaft 5. End of bimetal coil 6 which is through slot or fork in shaft 5 having

40 free room to slide back and forth along slot or fork in shaft 5 which passes through hole 13 in shank of casting 1 washer 9 being held against the shank of casting 1 by split pin 10. Shaft 5 which goes through hole 13 in shank of casting 1

45 extends through hole in concave spring 4 which hole in spring is only large enough to allow spring to go no further than the collar or shoulder at end of screw thread near end of shaft 5 concave side of concave spring 4 is turned away from casting 1 but next to quadrant shaped portal 2. Shaft 5 goes through hole in centre of quadrant shaped portal 2 which is held against the four outside ends of concave spring 4 by adjusting nut 7 which is held in position by locknut 8.

55 For operation of machine or device, smokestack

is to have a hole cut in it large enough but not too large to be properly covered by collar of casting 1. Casting 1 is attached closely and firmly to smokestack by screws or bolts through holes in collar of casting and through holes bored in 60 smokestack in similar relative positions.

Assuming that machine or device is properly installed and movable quadrant shaped portal 2 is in closed position, notch in side of quadrant against stop peg 3, as soon as stack begins to 65 heat up said quadrant shaped portal 2 will immediately commence to open and may continue to open until other notch in adjoining quadrant comes against stop peg 3 in casting 1. When in this position automatic draft regulating machine or device is wide open, allowing the cooler air to be drawn through the opening and up the chimney instead of the heat from the fire or furnace etc. Again as the stack cools off the movable quadrant shaped portal 2 closes up the 70 opening automatically, in similar manner.

This operation takes place as follows, heat inside smokestack causes bimetal coil 6 to twist, turning shaft 5 on other end of which is movable quadrant shaped portal 2, which can be revolved 80 to point where it comes against stop peg 3 in casting 1. At this point draft regulator is wide open and quadrant shaped portal 2 cannot move further in that direction. The bimetal coil 6 however may continue to keep on twisting and turning shaft 5 with split pin 10 and nuts 7 and 8. And if so then concave spring 4 becomes a slipping or frictional clutch against collar or shoulder on shaft 5, thus saving the bimetal coil 6 from 85 injury or damage caused by undue strain because 90 there is none.

As soon as stack begins to cool off, quadrant shaped portal 2 begins to close, and continues to close, turning in the opposite direction from when opening, until when stack is cold and then will 95 be completely closed. Frictional clutch again going into action after notch in quadrant shaped portal 2 returns to original closed position against stop peg 3.

The action of opening and closing of automatic draft regulating device depends on the amount of heat passing by bimetal coil 6 and escaping up the chimney, and where a constant heat is delivered into a firebox regardless of draft conditions 100 such as by an oil burner this type of draft regulator is especially effective in holding back the heat from going up the chimney as that very heat going up the chimney regulates it. Another feature of the machine is that if pushed out of 105 110

its proper adjustment it adjusts or corrects itself by means of its slipping or frictional clutch.

We are aware that prior to our invention automatic draft regulators have been made with 5 thermostatic bimetal coils, we therefore do not claim such a combination broadly; but what we do claim for our invention and desire to secure by Letters Patent is:—

We claim,—

10 In a draft regulator, a casting adapted to be connected to a smoke pipe or flue, a circular projection on said casting having a flat end surface, a coaxial bearing shank formed on said flat surface and projecting inwardly towards the pipe 15 or flue, a central bore in said shank having a shaft rotatably mounted therein, a bimetallic coil surrounding said shank and extending into the

pipe or flue, said coil having one end connected to the shank and the other end connected to the shaft, a circular plate mounted on or at the end of said shaft in close engagement with the flat surface, a frictional clutch connection between said shaft and plate whereby said plate will be rotated on rotation of said shaft by the bimetallic coil, a stop on said flat surface to limit the rotation of the plate in both directions, openings in said plate and flat surface, said openings being arranged to register when the plate is rotated in one direction and to be out of register when the plate is rotated in the opposite direction, substantially as set forth.
